RESERVOIR MARKING INSTRUMENT

Siegfried Lunzer, London, England

Application May 25, 1936, Serial No. 81,744
In Great Britain May 23, 1935

1 Claim. (CL. 120—43)

This invention relates to reservoir marking-instruments, and has for its object to provide an improved article of this kind which is simple in construction and reliable in operation, and is particularly suitable for writing or marking posters, announcements, display cards, and the like.

A marking instrument, according to my invention comprises a body or barrel whereto is fitted a section having a through passage; a collapsible ink reservoir or sac disposed within said body or barrel and attached to said section and with which an end of said section-passage communicates; a nozzle, or the like, secured to the section; and a felt or other absorbent marking tip or equivalent pad carried by said nozzle, or the like, and to the inner end of which tip or pad the other end of said section-passage opens; the arrangement and disposition of the parts being such that when said reservoir or sac is compressed by means of a lever and presser bar, or other sac-actuating mechanism, a charge of ink is ejected to saturate said tip or pad.

I will further describe my invention with the aid of the accompanying sheet of explanatory drawings which illustrate, by way of example only, one mode of carrying the same into effect.

In said drawing:—

Fig. 1 is a longitudinal sectional elevation of a marking-instrument constructed under this invention.

Fig. 2 is an elevation of the end section with collapsible reservoir attached, disconnected from the body or barrel of the instrument.

Figs. 3 and 4 are detail elevations, taken at right angles to each other, of the nozzle which carries a felt marking tip or pad.

In the views like characters of reference denote like or equivalent parts wherever they occur.

Referring to the drawing, *a* generally designates the tubular body or barrel of the marking-instrument which is made from casein, vulcanite, or other suitable material. Within the front of barrel *a* there is fitted a shouldered section *b* of similar material, a circular intermediate portion whereof being longitudinally serrated or scored at *b*¹ so that it will bite into and make frictional engagement with the inner wall or bore *a*¹ of barrel *a*: such wall or bore portion may also be correspondingly serrated or scored to co-operate in such engagement.

An enlarged portion of a tubular extension *b*² of the section is screw-threaded at *b*³ for engagement with a correspondingly internally screwed end of a metal tube or nozzle *c*, the opposite (outer) end whereof is flattened at *c*¹ to securely hold or carry a marking tip or pad of felt or other suitable or equivalent material *d*, the inner end whereof disposed within said tube or nozzle *c* touches or contacts with the mouth of tubular extension *b*² of the section, and which mouth constitutes the opening at this end of a passage *b*⁴ formed longitudinally through the section. The other end of the through-passage *b*⁴ communicates with a collapsible ink reservoir or sac *e* attached to a reduced end portion *b*⁵ of section *b* in similar manner to ink sacs of reservoir pens; in the example illustrated the sac *e* is actuated by presser bar *f* and lever *g* mechanism, also of the type as customary to sac self-filling reservoir pens.

The front end of the barrel *a* is screw-threaded for engagement with an end cap or cover *h*.

Ink ejected by actuation of the lever *g* to compress sac *e* saturates the absorbent marking tip or pad *d* ready for writing or marking by the end thereof protruding from nozzle *c*: in this manner the supply of ink to the tip can be regulated as required.

It will be obvious that any other sac-actuating means may be employed without departure from the invention.

What I claim as my invention and desire to secure by Letters Patent is:—

A marking instrument comprising a barrel carrying sac-actuating mechanism and whereto is fitted a section having a through passage; a tubular member forming an outward extension of said section; a collapsible ink sac disposed within said barrel and attached to said section and with which said section-passage and tubular extension communicate; a nozzle encompassing the tubular extension and removably fitted to the section; and an absorbent marking tip fixedly secured to said nozzle and to the inner end of which tip the adjacent end of said tubular extension makes contact: the arrangement and disposition of the parts being such that when said sac is compressed by means of the actuating mechanism, a charge of ink is ejected to saturate said absorbent tip.

SIEGFRIED LUNZER.
